UNITED STATES PATENT OFFICE.

J. EWING, OF NEW YORK, N. Y., ASSIGNOR TO FREDERICK V. RUSHTON, OF SAME PLACE.

IMPROVED STOPPER FOR BOTTLES.

Specification forming part of Letters Patent No. **20,843**, dated July 6, 1858.

To all whom it may concern:

Be it known that I, JAMES EWING, of the city, county, and State of New York, have invented a new and Improved Stopper for Bottles Containing Soda-Water, Champagne, and other Gaseous Liquids; and I do hereby declare that the following is a full and exact description thereof, to wit:

The nature of my invention consists in applying to bottles containing gaseous liquids confined under high pressure a valve-stopper by means of which the liquids can be drawn off without allowing the escape of gas, as shown in the drawings hereto annexed, making part of this specification, in which—

Figure 1 is a vertical section through the stopper. Fig. 2 is a horizontal section through the line *a b* in Fig. 1, and Fig. 3 is a representation of the stopper affixed to the bottle.

A is the valve case or chest, with the cork-tube *E* passing through or partly through the cork *C*. *B* is the valve, with a screw-thread working in the valve-chest *A*, by means of which it is forced down to its place with a wrench, *D*, affixed to the nut *N*. *b* is a cylin-

drical opening in the valve passing down to near the seat end where it has one or more openings, *c*. *d* is a packing of any substance to prevent the passage of liquid or gas between the valve and valve-chest. *e* is a washer which, when the valve is screwed down, is pressed tightly upon the valve-seat. *f* is a flange to protect the cork. The cork is secured to the bottle-neck by the straps *G* attached to the flange *f*. When the valve is open, as shown in the drawings, the fluid passes through the tube *E* and around the base of the valve, passing through the openings *c* and out of the opening *b*.

What I claim as an improvement in bottle-stoppers for bottles containing gaseous liquids confined under high pressure is—

The arrangement of the tubular stem-valve *B* within the chest *A*, with the cork-tube *E*, the whole being constructed and operated substantially as herein set forth.

JAMES EWING.
